UNITED STATES PATENT OFFICE.

PAUL F. SHIVERS, OF WABASH, INDIANA, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE.

FLUID-FUEL-BURNER CONTROL.

Application filed May 7, 1927. Serial No. 189,478.

The object of my invention is to provide a simple and efficient means for automatically controlling the action of a fluid-fuel burner so that it may be depended upon to permit 5 automatic normal operations of the burner but will prevent delivery of fuel in all cases of accidental failure of ignition or combustion.

The accompanying drawings illustrate my 10 invention diagrammatically, Fig. 1 showing one form of interlock switch, and Fig. 2 showing another.

Flow of current from the main power leads 10 and 11 is controlled by a room thermostat 15 T of any desired type capable of properly controlling the current. Other associated control mechanism, such for instance as a boiler control 13 or pressure control may be coupled in at this point. Wire 12 connects 20 lead 11 with T.

Leading from the thermostat T is wire 14 which connects to the bi-metallic thermostatic blade 15 of the warp switch W. Electrically connected to the blade 15 is one end 25 of the heating coil 16 connected by wire 17 to a terminal 18 of the combustion-control C.

The combustion-control C is a circuit determining element sensitive to combustion conditions closely adjacent the burner and 30 may conveniently be a well-known thermostatic device which, while movable through a wide range, serves to change circuits promptly upon rise or fall of temperature.

Paired with terminal 18 is a terminal 19 35 connected by wire 20 with blade 15 and by wire 21 with terminal 22 of the interlocking switch L. Paired with terminal 22 is a terminal 23 connected by wire 24 with the tongue 25 of the warp switch W, said tongue being 40 insulated from blade 15 and normally held by blade 15 in contact with terminal 26 against the bias of spring 27.

Terminal 26 is connected by wire 28 with the stator 29 of an oil valve motor VM, the 45 opposite end of said stator being connected by wire 30 with the main lead 10.

Wire 24 also leads to the terminal 31 in the combustion-control C, said terminal being

associated with terminals 32 and 33. Terminal 33 is electrically connected with terminal 19 and wire 20. A globule of mercury 39 may electrically connect terminals 31—32—33 or terminals 18—19.

Terminal 32 is connected by wire 34 with the electric ignition mechanism I which, in 55 the present instance includes the spark mechanism 35 and the electrically controlled pilot-gas-valve 36, the elements of the ignition mechanism being connected by wire 37 with the main lead 10. This ignition mechanism 60 is well known and needs no further illustration.

Terminals 22 and 23 form part of a switch mechanism which, in Fig. 1 is a mercury tube having the mercury 40 which is normally 65 away from terminals 22 and 23, i. e., when the oil valve is closed.

Terminal 18 is connected by wire 44 to a terminal 45 of a fuel motor switch S and the terminal is paired with a terminal 46 in a 70 mercury tube 47, the circuit at terminals 45 and 46 being normally open. Terminal 46 is connected by wire 48 with one side of the fuel motor M, the other side of said fuel motor being connected by wire 49 with wire 75 30 and one end of the stator 29.

The rotor of the valve motor VM is connected by a train of reducing gears 50 with a reciprocable plunger 52 of an oil valve 53 which controls flow of fuel to the burner. 80 Valve 53 is normally closed by a spring 54 which biases the plunger to closed position against the action of the valve motor. The details of construction of this valve form the subject matter of my co-pending application 85 Serial No. 111,154. In Fig. 1 the two switches S and L are carried by a pivoted carrier 55 pivoted at 56 and connected at 57 to plunger 52, the arrangement being such that terminals 45—46 and 22—23 are electrically connected only when the valve is 90 open.

In Fig. 2 the construction and arrangement are the same except that instead of the mercury tube L, I provide a terminal 22' 95 biased to open position by spring 60 and en-

gaged by plunger 52 against the bias of the spring. Terminal 22' is brought into contact with terminal 23' by the opening movement of the oil valve.

5 Terminal 22' is electrically connected with blade 15 and terminals 19 and 33 while terminal 23' is electrically connected with terminal 31 and leaf 25.

The operation is as follows:

10 The diagram shows the parts in the positions occupied when there is no call for heat.

When heat is called for the room thermostat or its equivalent, will close the circuit 11-12-14-20-33-32-34-1-37-10 to

15 produce ignition for fuel to be delivered at the burner. It also closes the circuit 11-12-14-20-33-31-25-26-28 and the stator 29 of the oil valve motor VM, thus starting the oil valve motor in opening direction against the bias of the return spring 54 which acts on plunger 52. This swings the interlock switch L and motor switch S.

Shifting switch S closes the circuit 11-12-14-15-16-17-44-45-46-48-M-25 49-30-10 and starts motor M to deliver fuel to the burner, the oil valve 52 being already open. Shifting switch L closes the circuit 11-12-14-20-21-22-23 (22'-23') in Fig. 2) 24-25-26-28-29-30-10 thus 30 providing a maintaining circuit for the fuel valve motor upon break of the circuit through 33-31 when the combustion control is heated.

The circuit through the motor M includes the heating coil 16 of the warp switch W so 35 that if there is no ignition and consequent heating of the combustion control or if, at any time there is a failure of combustion and a return of control C to cold position, the warp switch will be heated so as to cause a break 40 between 25 and 26 thus breaking the valve motor circuit and permitting the spring 54 to return plunger 52 to its normal position, thereby breaking the circuit of motor M at 45-46. Switch W must then be reset by 45 hand.

In normal operation a break at the room thermostat, due to sufficient heating of the adjacent space, breaks the circuit of the fuel valve motor VM and fuel motor M and permits the parts to return to cold position.

50 While I have illustrated mercury tube switches at various points it will be readily understood that any desired form of circuit breaker suitable for handling the necessary current may be substituted without departing from my invention. It will also be understood that the details of motor VM and its connection with the switches actuated thereby may be considerably modified and that 55 it is not absolutely essential that this motor actuates a fuel valve because, while such a valve is quite desirable to insure against leakage of fuel past the fuel delivering apparatus driven or controlled by motor M, such 60 apparatus controlled by motor M may be sole-

ly relied upon to control the flow of fuel. For convenience motor M may be called the fuel motor and motor VM may be called the supplemental motor. The details of the warp switch may be varied, the essential characteristic being that there be a retarded circuit-breaking action after a predetermined time interval of current flow in the absence of combustion at the burner, and the term "warp switch" in the claims is used to designate such a device generally, and the term "heating" coil is used to designate generally the element thereof electrically causing circuit-breaking action.

70 The fuel motor may drive or control a fuel pump or other fuel-flow control means and may drive movable parts of the burner proper.

The term "room thermostat" is used to designate a remote circuit-controlling element sensitive to thermal or other conditions to 85 be affected by the burner.

These various details may be varied through a wide range without departing from my invention.

I claim as my invention:

1. In a control system for fluid fuel burners, a fuel motor, an energizing circuit for said fuel motor and comprising a circuit breaker and the heating coil of a warp switch, a supplemental motor, an energizing circuit 95 for said supplemental motor comprising the warp switch and a circuit breaker subject to combustion conditions adjacent the burner, a maintaining circuit for the supplemental motor comprising the warp switch and a circuit breaker subject to action of the supplemental motor, means actuated by the supplemental motor for shifting the circuit breakers of the fuel motor circuit and the supplemental motor maintaining circuit, and a circuit breaker subject to combustion conditions adjacent the burner and arranged to shunt the heating coil during combustion.

2. In a control system for fluid fuel burners, a fuel motor, an energizing circuit for 110 said fuel motor and comprising a circuit breaker and the heating coil of a warp switch, a fuel valve, a supplemental motor for opening said fuel valve, an energizing circuit for said supplemental motor comprising the warp switch and a circuit breaker subject to combustion conditions adjacent the burner, a maintaining circuit for the supplemental motor comprising the warp switch and a circuit breaker subject to action of the supplemental motor, means actuated by the supplemental motor for shifting the circuit breakers of the fuel motor circuit and the supplemental motor maintaining circuit and a circuit breaker 115 subject to combustion conditions adjacent the burner and arranged to shunt the heating coil during combustion.

3. In a control system for fluid fuel burners, a fuel motor, an energizing circuit for 120 said fuel motor comprising a circuit breaker

actuated by the supplemental motor for shifting the circuit breakers of the fuel motor circuit and the supplemental motor maintaining circuit, an electric ignition means and an energizing circuit for said ignition means comprising a circuit breaker subject to combustion conditions adjacent the burner, and a circuit breaker subject to combustion con-

ditions adjacent the burner and arranged to shunt the heating coil during combustion. 10

In witness whereof, I, PAUL F. SHIVERS, have hereunto set my hand at Wabash, Indiana, this 30th day of April, A. D. one thousand nine hundred and twenty seven.

PAUL F. SHIVERS.
